UNITED STATES PATENT OFFICE.

RICHARD BRENNER, OF CHICAGO, ILLINOIS, ASSIGNOR TO KAESTNER & HECHT COMPANY, OF CHICAGO, ILLINOIS, A CORPORATION OF ILLINOIS.

DOOR-LOCK AND DOOR-SWITCH FOR ELECTRIC ELEVATORS.

1,209,637.

Specification of Letters Patent. Patented Dec. 19, 1916.

Application filed August 26, 1915. Serial No. 47,548.

To all whom it may concern:

Be it known that I, RICHARD BRENNÉ, a citizen of the United States, residing at Chicago, in the county of Cook and State of Illinois, have invented certain new and useful Improvements in Door-Locks and Door-Switches for Electric Elevators, of which the following is a description.

the following is a description:

This invention relates particularly, although not exclusively, to electric elevators of the class in which the motor-controlling mechanism may be operated by means of push buttons to cause the car to start and to stop automatically at any desired floor. At each floor is provided a door by means of which persons may enter and leave the car. Each door is normally locked.

One of the objects of this invention is to provide improved means for preventing a person from unlocking any of the doors except the door at the floor to which the car is destined, and for preventing the lock of the last mentioned door from being operated until the car has stopped moving.

25 Another object of the invention is to provide improved means for disabling the motor-controlling mechanism when any one of the doors is opened, in order to prevent the car from being started while a door is open.

ear from being started while a door is open.

30 In the accompanying drawings, Figure 1 is a diagram illustrating one embodiment of my invention. Fig. 2 is a detail view of the door-locking means. Fig. 3 is a sectional view taken approximately in the plane of dotted line 3-3 of Fig. 2.

35

Fig. 1 indicates three floors of a building. Each floor is provided with a sliding door 1 opening into the elevator shaft. The elevator car is not shown.

40 2 denotes a controller by means of which the motor (not shown) is started and stopped. This controller may be of any suitable character, as, for example, that shown in Patent No. 1,100,134, dated June 45 16, 1914. The motor is suitably connected to a hoisting drum 3 by means of which the elevator car is raised and lowered.

Each of the doors 1 is provided with a lock comprising a hand lever 4 having a handle 5 at its upper end. Intermediate its ends the lever 4 is pivoted to a vertical arm 6 which is pivoted at 7 to the door. Rigid with the arm 6 is a latch 8 adapted to pass through an opening 9 in a lock casing 10.

which is fixed to the door jamb. When in operative position the hook of the latch 8 lies behind the portion 11 of the lock casting. A spring 12 normally holds the latch 8 in the position shown in Fig. 2.

The means for preventing the latch 8 at 60 any given floor from being swung upwardly out of engagement with the portion 11 until the car has arrived at the given floor and has come to a stop comprises a member 13 having a chamber into which the free end 65 of the latch 8 may extend, the member 13 being vertically slidable in guides 14 in the lock casing 10.

A spring 15 tends to raise the member 13, the upward movement of said member being limited by impingement against the part 16. Upon the member 13 are formed one or more locking teeth 17 arranged to be engaged by a dog 18 pivoted at 19 in the lock casing 10. Rigid with the dog 18 is an arm 20 which is rigidly connected to the stem 21 of an armature 22, said armature being arranged to be lifted by an electromagnet 23. One terminal of the electromagnet 23 is connected to a wire 24 which is connected to a source of constant supply of electric current. The other terminal of the electromagnet 23 is connected by means of a wire 25 to the pole 26 of a switch 27 in the lock casing 10. The other pole 26a of the switch 27 is connected by means of a wire 28 to a suitable circuit-closer associated with the floor-stop device. To distinguish between the wires 28

device. To distinguish between the wires 28 at the different floors, said wires are indicated in the diagram as 28^a, 28^b, 28^c. A circuit may be closed across the contacts 26 and 26^a by a contact 29 which is secured to a plunger 30. A spring 31 normally holds the contact 29 out of engagement with the contacts 26 and 26^a. To the lower end of the hand lever 4 is pivoted a push pin 32 which extends through a guide 33. The push pin 32 is arranged to bear against the plunger 30. When the upper end of the hand lever 4 is swung toward the right (Fig. 2), the push pin 32 will be pressed against the plunger 30, whereby the contact 29 will be moved into engagement with the contacts 26 and 26^a. If the car be standing still at the floor at which the given hand lever 4 is located, a circuit will be closed (by the circuit-closer associated with the floor-stop device) through the electromagnet 23 and the arma- 90 95 100 105

ture 22 will be raised, thereby withdrawing the dog 18 from engagement with the member 13. Continued pressure on the handle 5 (toward the right, Fig. 2) will cause the latch 8 to swing upwardly, the member 13 being raised by the spring 15. As soon as the latch 8 is clear of the portion 11 the continued pressure on the handle 5 will cause the door to open. As the door is being opened the push pin 32 recedes from the plunger 30, whereupon the spring 31 opens the switch 27, thereby deenergizing the electromagnet 23.

The circuit-closer hereinbefore referred to is indicated diagrammatically at 34. Said device comprises a disk 35 which is arranged to be driven in any suitable manner from the hoisting drum. The disk 35 carries a piece of insulating material 36 which is curved upon the arc of a circle concentric with the axis of the disk 35.

37 is an electric contact in the insulating piece 36. The contact 37 is connected in any suitable manner to a wire 38 which extends to one pole of a switch 39. The other pole of said switch is connected to a wire 40 which communicates with the source of constant supply of electric current. The switch 39 is normally closed. When the controller 2 is actuated to close the motor circuit, said controller opens the switch 39. This may be accomplished in any suitable manner; herein is diagrammatically shown a slidable member 39^a which is engaged by the controller switch member 2^a and moved to swing the movable element of the switch 39 away from the stationary elements of said switch.

The wires 28^a, 28^b and 28^c extend to stationary contacts 28', 28'' and 28''' respectively. These contacts are arranged in position to be engaged by the movable contact 37. When the car is level with the first floor, the contact 37 is in engagement with the contact 28'. When the car is level with the second floor, the contacts 37 and 28'' are in engagement, and when the car is at the third floor the contacts 37 and 28''' are in engagement.

It will be seen that the latch 8 at any given floor cannot be disengaged from the portion 11 until a circuit has been completed through the electromagnet 23 at three different points, namely, the switch 27, the floor-stop contact 37 and the contact corresponding to the given floor, and the switch 39. Since the switch 39 is open when the motor is running, and since the contact 37 does not engage the proper contact except when the car is at the given floor, it will be seen that the car must be standing still at the given floor before the door can be unlocked. In the diagram the car is presumed to be standing at the third floor.

In the operation of closing the door, the beveled surface 8^a of the latch 8 strikes the

portion 11 and is thereby raised to pass over said portion 11, the latch at the same time entering the member 13. As soon as the hook of the latch has passed the portion 11 the spring 12 pulls the hook down behind the portion 11, and also pulls the member 13 down into normal position. The spring 12 is stronger than the spring 15.

The means for preventing the car from being started while any door is open, comprises a switch 41 at each floor, said switches being connected in series with the controller 2 so that when any one of the switches 41 is open, the controller 2 cannot be operated to supply current to the motor. Each of the switches 41 comprises two stationary contacts 42 and a movable contact 43, said movable contact being connected to the member 13. The switches 41 are normally closed, but when any one of the doors 1 is opened, the corresponding switch 41 is opened through the rising of the member 13. It will be seen that while any one of the doors is open the car cannot be started.

As will be readily understood, the door lock and door switch herein disclosed are adapted for use in electric elevators of other types than the automatic push-button type.

I claim as my invention:

1. An elevator system having, in combination, a door-locking member, a handle for operating said member, a lock for said member, an electromagnet for operating the lock, a circuit for the electromagnet, a switch in said circuit arranged to be closed by said handle, a controller, a switch in said circuit arranged to be opened by the controller, a hoisting drum, and a circuit-closer operated by the drum and included in said circuit.

2. In an elevator system, a pivoted latch, a casing having a portion adapted to be engaged by the latch, a member chambered to receive the end of the latch, said member being movable in said casing, a spring tending to move said member in one direction, a dog arranged to lock said member against such movement, an electromagnet for withdrawing the dog, a circuit for the electromagnet, a switch in said circuit, a hand lever for disengaging the latch from the casing, a member connected to the hand lever for closing the switch, and a spring for moving the latch into engaging position, the last mentioned spring being stronger than the other spring.

3. In an elevator system, a pivoted latch, a casing having a portion adapted to be engaged by the latch, a member chambered to receive the end of the latch, said member being movable in said casing, a dog arranged to lock said member, an electromagnet for withdrawing the dog, a circuit for the electromagnet, a switch in said circuit, a hand lever for disengaging the latch from the casing, and a member connected to the hand lever for closing the switch.

4. An elevator system having, in combination, a door jamb, a door, a door-locking member on the door, a handle for operating said member, and for moving the door, a lock for said member on the door jamb, an electromagnet for operating the lock, a circuit for the electromagnet, and a switch on the door jamb, said switch being included in said circuit and being arranged to be closed by said handle. 45
5. An elevator system having, in combination, a door-locking member, a member associated therewith, a lock for said door-locking member, an electromagnet for operating the lock, a circuit for the electromagnet, a normally open switch in said circuit adapted to be closed by said associated member, a controller, and a normally closed switch in said circuit arranged to be held open by the controller while the motor is running. 50
6. An elevator system having, in combination, a door-locking member, a lock for said member, an electromagnet for operating the lock, a circuit for the electromagnet, a hoisting drum, a circuit-closer operated by the drum and included in said circuit, a part for operating said door-locking member, and a second circuit-closer included in said circuit and operable by said part. 55
7. An elevator system having, in combination, a door-locking member, a handle for operating said member, a lock for said member, an electromagnet for operating the lock, a circuit for the electromagnet, and a switch in said circuit arranged to be closed by said handle. 60
8. An elevator system having, in combination, a door jamb, a door, a switch on the door jamb which is normally open when the door is closed, a handle on the door for opening the door, and a switch-operating member mounted to travel with the door, 65
9. In an elevator system, a pivoted latch, an arm connected to said latch, a lever pivoted intermediate its ends to said arm, a handle on one end of said lever, and a switch-operating member on the other end of said lever. 70
10. In an elevator system, a pivoted latch, an arm extending upwardly from the pivoted center of said latch, a lever pivoted intermediate its ends to said arm, a handle on the upper end of said lever, and a switch-operating member on the lower end of said lever. 75
11. An elevator system having, in combination, a door locking member, a lock for said member, an electromagnet for operating the lock, a circuit for the electromagnet, an independent circuit, a controller in said independent circuit, a normally closed switch in said electromagnet circuit arranged to be held open by the controller when said independent circuit is alive, and a switch in said independent circuit arranged to be closed by said door locking member whereby said controller may open 80 said normally closed switch.
12. An elevator system having, in combination, a door-locking member, a member associated therewith, a lock for said door-locking member, an electromagnet for operating the lock, a circuit for the electromagnet, a switch in said circuit adapted to be closed by said associated member, a controller, and a switch in said circuit arranged to be opened by the controller. 85
